UNITED STATES PATENT OFFICE

NATHANIEL B. AUKERMAN, OF LAKewood, OHIO.

PROCESS OF AND MEANS FOR RECOVERING SILVER FROM PHOTOGRAPHIC AND OTHER BATHS.

1,425,935.

Specification of Letters Patent. Patented Aug. 15, 1922.

Application filed May 31, 1919. Serial No. 300,891.

To all whom it may concern:

Be it known that I, NATHANIEL B. AUKERMAN, a citizen of the United States, and a resident of Lakewood, in the county of Cuyahoga and State of Ohio, have invented a new and useful Process of and Means for Recovering Silver from Photographic and Other Baths.

I believe myself to be the first and original inventor of a galvanic or electro-chemical method for recovering silver from solutions of this general character, and the means for which comprises copper and zinc elements partially insulated from each other and related as herein shown and described so as to set up within the complete unit an electro-chemical action, causing not only the precipitation of the silver, but also causing it to be deposited or plated on the wall of the unit or device in such a pure and compact mass that the silver recovered is nearly of a pure bullion standard.

It is estimated that from five to seven tons of silver pass through the sewers in the United States alone each month and is lost for the obvious reason that no successful or practical means for the recovery thereof is known, and which I can reclaim by my simple and inexpensive process without special care, time or trouble and which requires no appreciable extra space in the baths. Thus this loss can be turned to profit and the silver supply of the country correspondingly conserved.

In the accompanying drawings Fig. 1 discloses a perspective view of a partially assembled unit or device embodying my invention, and with one of the outer or wooden sides thereof and the binding screws therein at the right of the central figure and a sheet of blotting paper, or its equivalent, at the left.

Fig. 2 is a perspective view of the device complete and ready for use, and Fig. 3 is a perspective view of a bath or cell broken away at one side and disclosing one of my units or devices therein. As many more such units may be added as required for any given size of bath, and which may be connected or used separately as desired.

In the device as thus illustrated A and E, respectively, show wall pieces of wood or other suitable non-metallic material of a size, say 3" x 10" $\frac{1}{8}$ ", but which may be of

any suitable size according to the size of the 55 bath or receptacle.

B shows sheets of copper like those used by photo engravers and for which purpose scrap copper may be employed, but I am not limited to copper as other material such as 60 iron, brass, and the like are found to be of nearly equal value.

C shows sheets or layers of zinc and which are shown as the same width and thickness as the copper but shorter and interposed between the copper piles on the sides. Zinc chips or filings may be used instead of sheets.

F shows strips of blotting paper, wood or other porous material which absorb sufficient moisture to make good galvanic action in the bath solution and are used to separate each plate or layer of copper and zinc, respectively. A single sheet of these strips is shown to be slightly narrower and 70 shorter to allow the copper elements to be sufficiently exposed in the solution to create the proper electro-chemical action and said sheets are formed with a notch or recess n 75 in each end corresponding to the width of 80 the middle or zinc pile, and which notch also accommodates the screws s which pass through the outer wall E and fasten into the opposite wall A and bind the elements of the unit securely together.

The space between the copper piles at the ends of the shorter zinc pile shown at D, Fig. 2, is packed with a greasy wax or other water and acid resisting material which acts to insulate the zinc from direct action of the 90 bath solution and protects the zinc from too rapid disintegration.

This greasy material also protects the screws at these points and at the heads thereof, which are sunken below the surface of 95 the wood and filled over the top with the same material, as at b Fig. 1. For this purpose I have found a composition of rosin four parts, petroleum jelly two parts, paraffin two parts, and sulphur flour two 100 parts very satisfactory, but any other suitable material or composition may be employed.

The unit as a whole is represented in Figs. 2 and 3 by G and the bath or cell by H.

In operation this unit or electro-couple is 105 immersed in the photographic solution or bath and the silver recovered by an electro-

lytic action which builds up the silver on the insulating or covering medium instead of on the elements of the electro-couple. Thus, the active elements of the electro-couple are separated by the absorbent non-conductor strips F and also confined between and covered by the wooden pieces A and E, respectively, to partially insulate the elements from the solution and restrain the action of the solution on the elements, and to build up the metal in the solution upon the surfaces directly exposed to the solution. In this connection it should be noted that the copper and zinc elements in each layer or lamination of the electro-couple are separated by an absorbent strip F which prevents the metal in solution from being deposited upon the major plane surfaces of the elements and causes the deposition to take place mainly upon the insulating or resistance covering for the elements from which it can be readily stripped and released. In this way the silver in the bath is completely recovered and the bath rejuvenated or regenerated.

What I claim is:

1. The process herein described of recovering silver in solution in a photographic or like bath, consisting in subjecting the solution to the electro-chemical action of an electro-couple and in restraining the free action of the solution and building up a silver deposit mainly apart from the active elements of the electro couple.

2. A medium for reclaiming silver from hyposulphite and other baths containing silver in solution, comprising an electro-couple and means contiguous to the elements thereof adapted to restrain the free action of the solution and effect the electro-deposition of silver in a mass thereon.

3. An electro-couple for reclaiming silver from baths containing silver in solution, comprising a plurality of layers of different metals and interjacent layers of porous material, and a covering of non-metallic material.

4. An electro-couple for reclaiming silver in solution, comprising a plural number of layers of abutting plates having insulating material between the respective layers, and binding means uniting said plates and material tightly together.

5. An electro-couple for recovering metals in solution, comprising abutting copper and zinc plates arranged in layers with non-conducting material intervening said layers, and means adapted to insulate said zinc plates from direct contact with the solution.

6. A medium for recovering silver from baths containing silver in solution, comprising laminations of abutting elements adapted to set up an electro-chemical action, porous material interposed between said laminations, and a covering of non-metallic material for the outer laminations.

7. A process of recovering a metal in solution, consisting in immersing an electro-couple in the solution and slowing down the rate of deposition of the metal to obtain a crystalline coherent deposit upon said electro-couple.

8. A process of recovering a metal in solution, consisting in placing an electro-couple in the solution in association with a resistance medium adapted to receive the electro-deposition of the metal on the exposed surfaces thereof.

9. A process of recovering a metal in solution, consisting in effecting a resistance between the elements of an electro-couple in the solution concurrently with the deposition of the metal.

10. A process of recovering a metal in solution, consisting in partially enclosing the elements of an electro-couple within a non-metallic covering of low conductivity and immersing said covered electro-couple within the solution until complete electro-deposition of the metal takes place.

Signed at Cleveland, in the county of Cuyahoga, and State of Ohio, this 12 day of May, 1919.

NATHANIEL B. AUKERMAN.
